UNITED STATES PATENT OFFICE.

JAMES E. SHAW, OF GERMANTOWN, PENNSYLVANIA.

KNIFE SHARPENER.

Application filed August 21, 1924. Serial No. 733,356.

To all whom it may concern:

Be it known that I, JAMES E. SHAW, a citizen of the United States, residing at 5150 Wakefield Street, Germantown, county 5 of Philadelphia, and State of Pennsylvania, have invented a certain new and useful Improvement in Knife Sharpeners, of which the following is the specification.

My invention relates to the art of tools 10 or devices adapted for the sharpening of knives, scissors, or other blades, and it has for its object to produce a device through which the blade is designed to be drawn in order to produce the sharpening effect.

Another object is to produce a device of 15 this character which will only cut away or turn (in the sharpening operation) one side surface of the blade, the other surface not being affected in any manner by the drawing of the knife through the device.

Another object is to produce a device of 20 this character in which the blade will be sharpened with a convex rather than a concave edge, as is produced by most sharpeners.

A further object is to construct the device in such a manner that the drawing of 25 the blade through one side of the device will sharpen, in a convex manner, one side 30 of the blade, and the drawing of the blade through the other side of the sharpener will sharpen the reverse side of the blade, the two sides obviously mating to form a keen, sharp edge when the blade has been properly sharpened.

A further object is to produce a device for 35 sharpening blades which will avoid the forming of a serrated edge, and which will not tend to wear away the material of the blade to any marked extent whatsoever.

My invention consists of certain details of construction hereinafter set forth, pointed out in my claims, and illustrated in the accompanying drawings, in which—

Fig. 1 shows a perspective view of my 45 device, a knife being drawn therethrough for sharpening.

Fig. 2 shows a transverse sectional view 50 of a knife, illustrating the manner in which the blade is sharpened.

Fig. 3 is a detail view of the guide member I employ.

Fig. 4 is a detail view of side elevation of 55 one of the cutting plates.

Fig. 5 is a transverse sectional view of my 60 device, the section being taken through the

guide member and one of the cutting plates so as to illustrate the manner in which they are joined to the body member.

Fig. 6 shows a detail view of the mating 60 position of one of the cutting plates with the guide member to form notch into which the blade is inserted for sharpening purposes.

Referring to the accompanying drawings 65 the reference numeral 10 is used to indicate a base support, or the like, to receive the functioning elements constituting my device. This base may be of any desired material, and may have a handle such as shown at 11 70 so that the device may be used as a tool and simply held in the hand and the blade drawn through the operating parts, or this base may be bolted to a table, or the like, in any desired manner (no such manner being illustrated) if preferred. On this base I have mounted in stationary position a guide member 12 having its sides 13 and 14 on an inclined plane, or they may be vertical, as shown in dotted lines, and mating with these 75 inclined planes are the concave edges of the cutting, or sharpening, plates 15 and 16 which I employ. These plates are arranged to face each other in the manner shown, their base portions practically contacting and the 80 concaved facing edges, providing a considerable space to extend between them at their upper edges. The guide member 12 lies flush against the plates 15 and 16, and belts secure the guide member and sharpening plates in their respective and relative 85 positions, fixed with relation to each other. The guide plate extends upwardly with the cutting plates and lies flush against one side of the said plates, the upper end of the guide 90 member being smaller than the lower end, as hereinbefore stated, this construction forming the two notches 17 and 18 one between the cutting edge of the plate 15 and the inclined or vertical edge 13 of the guide member 12, and the other notch being formed between the cutting edge of the cutting plate 16 and the inclined or vertical edge 14 of the 95 guide member 12. These two notches are designed to be, and by construction are, of 100 substantially the same size and formation.

From this construction it is obvious that the cutting edge of the cutting plate being concave from the base to the top of the cutting plate and the vertical or inclined edge 110 of the guide member being on a straight but vertical or inclined plane, the crossing of

the concave surface of the cutter with the straight surface of the guide member will cause the notch to be concave on the cutter side and straight on the guide side. It is 5 also obvious that the concave side of the notches will be reversed as to each other.

In practical operation it being desired to sharpen a blade it is inserted in the notch 17 until the edge of the blade rests at the 10 angle formed by the concave edge of the cutting plate and the straight edge of the guide member. By pulling the blade through the notch and bearing slightly down upon the same the cutting plate cuts away 15 slightly the steel on that side of the blade and forms a convexed edge on that side of the blade, and at the same time sharpens the edge thereof. The blade is then inserted in the notch 18 and the other side of the 20 blade sharpened in like manner, thus forming a keen, sharp edge on the blade, both sides of which are convex. This very materially saves the steel in the blade, and the edge is not serrated or uneven, but smooth 25 and keen, and it has been demonstrated that the edge thus produced on a blade is much more satisfactory and efficient than the edge produced by the usual types of sharpeners.

By my construction scissor blades, which 30 are only sharpened on one surface thereof may be easily and quickly sharpened, one blade being drawn through one of the notches in the device and the other blade being drawn through the other notch. It has also 35 been demonstrated that blades being sharpened with this convex edge give not only a more substantial cutting edge, but a much better service, this being proven by demonstration in the actual use of the sharpeners.

40 In the drawings I have illustrated simply

a preferred form of construction for my device, but I wish it understood that I do not desire to be limited to the construction shown or described in the specification, nor to limit the scope of the protection of my 45 invention except as set forth in the accompanying claims.

Having described my invention what I describe to secure by United States Letters Patent is:

50 1. A sharpener comprising a guide member with inclined edged surface and a cutting plate provided with a concave surface extending downwardly from its upper extremity, said concave edge crossing the vertical or inclined surface of the guide member, so as to form a notch concaved on the cutting side and straight on the guide side. 55

2. A sharpener comprising a pair of cutting plates spaced from each other at their upper extremities and each provided with concave surfaces extending downwardly and on the inner side from their upper extremities, and a guide plate adjacent one side of the said plates and extending upwardly between them, said plate having inclined edges to cross the respective concave edges of the cutting plates so as to form on each side of the guide member a notch concaved on its outer surface and straight on its inner surface. 60

65 3. A sharpener for blades comprising a notch formed with one straight side, its other side being formed with a concave cutting plate. 70

75 4. A sharpener comprising a cutting plate whose opposite edges are concave, being narrow at the top of the concave edges and broad at the bottom of the concave edges.

JAMES E. SHAW.
